UNITED STATES PATENT OFFICE.

CARL GABRIELSON, OF SYRACUSE, NEW YORK, ASSIGNOR TO L. C. SMITH AND BROS. TYPE-WRITER COMPANY, OF SYRACUSE, NEW YORK, A CORPORATION OF NEW YORK.

TYPE-WRITING MACHINE.

No. 885,694.

Specification of Letters Patent.

Patented Sept. 10, 1907.

Application filed April 28, 1904. Serial No. 205,306.

To all whom it may concern:

Be it known that I, CARL GABRIELSON, a citizen of the United States, residing at Syracuse, Onondaga county, State of New York, have invented certain new and useful Improvements in Type-Writing Machines, of which the following is a specification.

This invention comprises improvements in the paper feeding mechanism of typewriting machines, the details of which will be described in the following specification, in connection with the accompanying drawings, in which the improvements are shown as applied to a "front strike" machine.

In the drawing, Figure 1 is a top plan view of parts of a typewriting machine, including the carriage and platen, with my improvements applied thereto; Fig. 2 is a right end view of the same, the knob for turning the platen being removed; Fig. 3 is a side view of the paper feeding devices and the type-guide, the platen being shown in outline; Fig. 4 is a front view of one of the fingers for holding the paper against the front of the platen and for indicating the printing line upon the paper; Fig. 5 is a detail sectional view on the line A—A of Fig. 1, showing the means for moving the paper guiding rollers out of engagement with the platen; Fig. 6 is a similar view on the line B—B of Fig. 1, showing the clamp for holding the tension adjusting sleeve; and Fig. 7 is a detail of part of Fig. 1, with the platen omitted.

Referring to the drawing, *a* indicates the carriage, the frame of which comprises a back bar *1* and end bars *2* and *3* projecting forwardly therefrom. The platen *4* is mounted upon the shaft *5* which is journaled in the ends of the carriage, and the carriage travels transversely of the machine frame *b* upon ball bearings *6*. The paper is conducted beneath the platen by a series of rollers *7* journaled upon a shaft *8* in the rear of the platen and a series of rollers *9* journaled upon a shaft *10* in front and below the platen. The shafts *8* and *10* are journaled in rockers *11* which are pivoted on arms *13* which are adjustably secured to a rock shaft *14*. The rollers on shafts *8* and *10* are spaced suitable distances apart by sleeves *12* upon the shafts. The shafts and rockers form a frame or cradle which is carried by the shaft *14*. As shown, the arms *13* are connected to the rockers *11* by pivot pins *15*, which pass through the rockers *11*, and a curved sheet metal guide *16* for the paper is pivotally supported on said pins by intermediate tongues *17* secured to the lower side of the guide and journaled upon said pivot pins. The forward end of this apron is normally pressed lightly against the forward side of the platen by springs *18* secured to the rockers *11* and bearing against the under side of the apron, and the rear portion of the apron hangs away from the platen to permit the paper to be readily in-

serted between the platen and the apron. The arms *13* are provided with split hubs *13a* and clamping screws *18* by means of which the arms may be adjusted and clamped upon the rock shaft. This rock shaft has its ends journaled in suitable bearings in the carriage frame, and the paper feeding rolls *60* are given the requisite pressure against the platen by means of a spring *19*. This spring is coiled around the rock shaft and has one end attached to a collar *20* (Figs. 1 and 5) secured upon the shaft by a set screw *21*, and its opposite end is secured to a sleeve *22* which fits *65* loosely upon the shaft and is normally held against rotation by a split hub or clamp *23*, Figs. 1 and 6. This hub or clamp, as shown, is formed integral with the carriage frame and the shaft and sleeve extend through it, the latter being adjustably secured by means *70* of the clamping screw *24*. The pressure of the various feed rollers upon the platen may be equalized by adjusting the arms *13* upon the rock shaft, so as to make the pressure of the rollers at opposite ends of the roller frame alike, and the degree of pressure of all the rollers *75* may be regulated by the adjusting sleeve *22*.

In order to withdraw the feed rollers from contact with the platen for the purpose of adjusting the paper, the collar *20* is provided with a radially projecting arm *25*, (Fig. 5) having an upturned end *26*, and a lever *27* *80* is journaled upon a stud *28* projecting from the carriage frame above said arm. The shorter arm *27a* of this lever is provided with a roller *29* which is adapted to bear upon and depress the arm *25* when the longer arm of the lever is pulled toward the operator. This depression of the arm *25* causes the rocking of shaft *14* and the withdrawal of the paper feed rollers from the platen. When the movement of lever *27* is reversed, the spring *19* returns the rollers to their positions against the platen, and normally holds the roll *29* against a stop *90*, *26*, and the lever *27* in its rearward position.

A plurality of paper-holding fingers *30* are pivotally connected to slides *31* which are adjustably secured upon a bar *32* arranged in front of and below the printing line of the platen said bar being secured at its ends *95* to the ends of the carriage frame. These slides and fingers are preferably made of sheet steel and each slide has overturned flanges or clips *33* fitting around the edges of the bar *32*. Each finger *30* is secured to its slide *31* by a hinge joint *34*.

A roller *35* is journaled in ears *36* projecting outwardly from the body of each finger, and this roller is normally pressed against the paper by means of a spring *37* arranged at the hinge joint. Stops *38* are provided to limit the movement of the fingers when the platen *105* is removed. Spring tongues *39* in the front of each slide *31* bear frictionally upon the bar *32* and retain the fingers in any desired position. It will be noted from an

inspection of Fig. 3 that the fingers do not bear upon the paper, but serve to guide the paper beneath the rollers 35 which hold it against the platen. There are 5 projections 39 at the inner sides of the fingers which serve as pointers to indicate the printing line. These indicators are desirable in writing upon ruled paper. When a ruled line is brought to register with the indicators, the machine will print on the upper side of the line. The slide portion of each finger is provided with 10 a stop piece 40 projecting forwardly from its lower edge. These stop pieces are arranged to engage the type-guide support 41 or some similar fixed obstacle to prevent the finger pieces from passing in front of the printing point. It is impossible, therefore, for the type to 15 strike the finger pieces at either end of the line.

It will be evident that the mechanism described may be varied more or less without departing from the spirit of the invention.

Therefore, without limiting myself to the precise 20 construction and arrangement of parts illustrated and described, I claim:

1. In a typewriting machine, the combination with the 25 platen, of a paper feeding mechanism comprising a rock shaft, arms on said rock shaft, rockers pivotally connected to said arms, roller shafts journaled in said rockers, a curved paper guide for directing the paper about the platen between the roller shafts, said guide being carried by said rockers, and springs for pressing the guide against the platen.

2. In a typewriting machine, the combination with the 30 platen, of a paper feeding mechanism comprising a rock shaft, a pair of arms adjustably mounted on said rock shaft, paper feed rollers carried by said arms, a spring operating on said rock shaft to hold the rollers against the platen, an arm fixed on said rock shaft, and a lever operating on said arm to rock the shaft for the purpose of withdrawing the feed rollers from the platen.

3. In a typewriting machine, the combination with the 35 platen, of a paper feeding mechanism comprising a bar supported on the carriage in front of the platen; slides upon 40 said bar, spring fingers carried by said slides, a type guide, and stops on said slides co-operating with the type guide for preventing the fingers from being moved past the printing point.

4. In a typewriting machine, the combination with the 45 platen, of a paper feeding mechanism comprising a bar supported on the carriage in front of the platen, slides upon 50 said bar, pivoted upwardly extending fingers carried by said slides, springs carried by the slides for forcing the fingers against the platen, and stops for sustaining the fingers when the platen is removed.

5. In a typewriting machine, the combination with the 55 platen and a bar adjacent to the platen, of a slide on said bar, a finger hinged to said slide, a spring tending to move the finger into engagement with the platen, and a stop fixed on the finger and adapted to abut against the slide to limit the movement of the finger.

In testimony whereof I have signed my name to this specification in the presence of two subscribing witnesses.

CARL GABRIELSON.
